UNITED STATES PATENT OFFICE.

CHARLES V. HANSON, OF FALL CITY, WASHINGTON.

QUICK-ACTING BOLT CLAMP.

Application filed October 20, 1921. Serial No. 509,156.

To all whom it may concern:

Be it known that I, CHARLES V. HANSON, a citizen of the United States of America, and resident of the city of Fall City, in the 5 county of King and State of Washington, have invented certain new and useful Improvements in Quick-Acting Bolt Clamps, of which the following is a specification.

My invention relates to quick acting bolt 10 clamps or devices which are intended to be used in connection with a bolt as a quick acting means for securing the holding down action of the bolt, thus eliminating the time consumed in removing and replacing nuts 15 and turning them down.

The object of my invention is to provide a device which may be used in certain situations and under certain conditions to apply 20 and to relieve the holding action of the bolts in a quick and easy manner.

The features of my invention which I believe to be new will first be described in the specifications and then particularly defined in the claims.

25 The accompanying drawings show my invention applied in constructions of somewhat varying form adapted for action under the same principle but under different conditions.

30 Figure 1 is a side elevation of a bolt having one form of my device applied thereto, showing the same in clamping or holding position.

Figure 2 is a side elevation of the bolt 35 showing the clamping device in section on the plane indicated by the broken line 2—2 in Figure 1.

Figure 3 is a side elevation of a modified 40 type of construction in which the same principle is employed.

Figure 4 is a central section taken through the holding device shown in Figure 3.

45 Figure 5 is a device of the same general construction as that shown in Figures 3 and 4, the position being that of Figure 3 except that the clamping member is released or thrown upward.

Figure 6 is a sectional elevation through 50 a clamping device designed for use in connection with a bolt which extends into and is supported by the surface against which the clamping is to be done.

Figure 7 shows in perspective the clamping lever constructed as is shown in Figure 6.

One of the principal applications of my invention is for the purpose of holding down covers to containers of various kinds which it may be necessary or desirable to frequently remove and replace. Another of the purposes for which the device is especially adapted is for clamping and holding such articles as the yoke-shaped plate which is commonly employed as a terminal for electric wires. There are many purposes to which the device is applicable and I do not desire to limit it to any particular use to which it is adapted.

In Figures 1 and 2 the device is shown as applied to a bolt which projects upward and is supported from a surface of the body against which it is desired to clamp any object. As shown in these two figures the object being held is indicated as the terminal 70 of an electric wire. The particular object being held is, however, immaterial. The bolt 1 is shown as screwed into and supported by a base surface or body 10. For the purpose of regulating the exact height 75 or projection of the bolt a locknut 11 is shown by the use of which the bolt may be fixed in any adjusted position.

The locking member consists of a lever 2 which is provided with two wings or plates 80 separated sufficiently to embrace the stem of the bolt. Upon the bolt beneath the head 12 is placed a collar or ring 3 which is free to turn upon the bolt. The clamping arm or lever 2 is pivoted upon the collar 3 by 85 pivot pins 21. The lower edges 22 of the wings 20 are so shaped as to form cam surfaces. These surfaces are so disposed that when the lever is down or in holding position as it has been shown in Figure 1, the 90 line of contact between the pivot 21 and the point of engagement with the member 4 which is being held down, is not towards that side of the central or axial plane of the bolt which lies toward the handle 2, but 95 preferably slightly to the other side so that there will be no tendency for the lever to be thrown upward or into released position by the pressure applied.

The action desired is equivalent to that secured in toggle joint levers which have been thrown so that their central pivot has passed the dead center. 100

In connection with a device of this sort it is desirable to have a slightly resilient action such that the parts may give a little 105 in throwing the lever down into locked position and yet so that it will hold securely. In 110

the construction shown in Figures 1 and 2 this has been secured by the use of a split or spring washer 5 interposed between the collar 3 and the head 12.

5 Figures 3 and 4 show a modified construction. In this the lever consists of a member 23 which has two arms lying one at each side of the bolt, these being connected towards one end by a central band 24. This 10 lever is pivoted at 21 to a nut 30 which is adjustable upon the bolt 1. This lever is provided with a resilient or spring extension 25 which engages with the object which is to be held down.

15 In the type of construction shown in Figures 3 and 4 the bolt 1 is supported from some point outside of or above the surface of the body 10 against which the clamping is to be done. In this case the resilient extension 25 may be continuous from side to side and swing under the end of the bolt. In the construction shown in Figure 6 in which the device is mounted upon a bolt supported from the surface 10 against 20 which the clamping is to be done, the plate 25 which forms this resilient extension must be provided with a slot as 26, which leaves two side strips 27 one at each side of the bolt for engagement with the body which is 25 to be clamped down.

30 With a device of this character the object being held is released by simply throwing down the clamping lever and secured by throwing up the lever. It thus enables de-

vices which are held down in this manner 35 to be quickly secured and released. Where such device requires a number of holding down bolts the time saved will amount to considerable.

What I claim as my invention is:

40 1. A quick acting bolt clamping device comprising a lever having wings pivoted at opposite sides of a bolt and a spring plate having a U-shaped bend with its ends secured to said lever to form an extension thereof 45 adapted to form the clamping surface, the arms of said U-shaped member being in planes which are substantially parallel with the pivot axis of the lever and at each side of the axis of the bolt.

50 2. A quick acting clamping device for bolts comprising a nut threaded upon the bolt, a lever pivoted upon said nut and having a resilient extension adapted to engage the object to be held, said parts being connected to hold the extension in alinement with the bolt when thrown into clamping position.

55 3. A quick acting bolt clamping device comprising a lever having wings pivoted at 60 opposite sides of the bolt, and a resilient extension from one end of said lever adapted to engage the object to be held when the lever is alined with the bolt.

65 Signed at Seattle, King County, Washington, this 15th day of October, 1921.

CHARLES V. HANSON.
